HIGH PRESSURE PUMPING SYSTEM

Clarence J. Coberly, San Marino, Calif., assignor to Kobe, Inc., Huntington Park, Calif., a corporation of California

Application July 12, 1957, Serial No. 671,622

7 Claims. (Cl. 103—46)

The invention which is the subject of this application relates to fluid operated pumps and pumping systems and a primary object of the invention is to provide a fluid operated pump and pumping system which utilize operating fluid pressures many times higher than those utilized heretofore to obtain numerous advantageous results, the present application being a continuation-in-part of my copending application Serial No. 598,785, filed July 19, 1956.

As general background, any fluid operated pump includes a pump section actuatable by a fluid operated engine section to pump fluid from a well in which the pump is disposed upwardly to the surface through a production tubing set in the well. More particularly, such a pump includes cylinder means having an inlet in communication with the well and having an outlet in communication with the lower end of the production tubing. Reciprocable in the cylinder means is an engine and pump piston means, comprising interconnected engine and pump piston elements, for pumping fluid from the well upwardly through the production tubing to the surface, reciprocatory movement of the engine and pump piston means resulting from the alternate application of operating fluid pressure and spent operating fluid or exhaust pressure thereto by an engine valve means forming part of the pump. The engine and pump piston means includes a transverse pump area which supports the entire column of production fluid between it and the surface, and which moves such column upwardly through the production tubing, during a working stroke of the piston means, the pump being provided with a working valve which prevents backflow into the well during such working stroke. In order to produce the working stroke of the piston means, it is provided with an engine area to which the operating fluid pressure is applied at least during the working stroke. In the case of a single-acting pump, to which the present disclosure will be restricted for convenience without necessarily limiting the invention thereto, the working stroke of the piston means occurs in one direction only and movement of the piston means in the opposite direction merely constitutes a return stroke, the pump being provided with a standing valve which prevents backflow from the production tubing into the well during such return stroke. Normally, the pump is so oriented and constructed that the working stroke of the engine and pump piston means occurs in the upward direction, the return stroke of the piston means thus being the downward stroke thereof.

A fluid operated pump of the foregoing nature may be utilized in either an open system, wherein the spent operating fluid is mixed with the production fluid and is returned to the surface through the production tubing, or in a closed system wherein the spent operating fluid is conveyed to the surface through a separate, return tubing. In the case of an open system, the exhaust pressure acting on the engine section of the fluid operated pump is the production column pressure, while, in a closed system, the exhaust pressure acting thereon is the

return column pressure. For convenience, the present disclosure will be restricted to a closed system without necessarily limiting the invention thereto.

Heretofore, fluid operated pumps, such as those disclosed in my Patents Nos. 2,081,220 and 2,473,864, and in my aforementioned copending application, have been provided with engine areas which are large in comparison to the pump areas thereof so that the pumping systems in which such pumps are incorporated must utilize large volumes of operating fluid at relatively low operating fluid pressures. For example, conventional fluid operated pumps are customarily provided with ratios of pump area to engine area ranging from 0.65:1 to 1.5:1 with the average being approximately 1:1. With such ratios, the operating fluid pressures utilized range approximately from 1,700 p.s.i. gauge to 3,800 p.s.i. gauge for the average pump depth setting of 5,000 ft.

Such low pump area to engine area ratios and the correspondingly low operating fluid pressures require large flows of operating fluid through the tubings of the hydraulic pumping system. Consequently, high fluid friction losses in the tubings through which the operating fluid circulates are experienced, particularly in wells having high productive capacities. Such fluid friction losses may be reduced to some extent by enlarging the tubings of the fluid operated pumping system through which the operating fluid flows, but this is expensive and the extent to which such tubings can be enlarged is severely restricted by the small diameter of the well bore.

Another serious disadvantage of prior fluid operated pumps is that the large engine areas previously utilized severely restrict the sizes of the production fluid passages through the pumps and the sizes of the working and standing valves incorporated therein, the sizes of such passages and valves conventionally being selected on the basis of a compromise dictated by the space occupied by the engine section of the pump. As will readily be understood, the small production fluid passages and valves resulting from such a compromise produce serious fluid friction losses within the pump itself, these being in addition to the losses in the tubings of the system resulting from the large volumes of operating fluid which must be handled in a low pressure system wherein the pumps have low ratios of pump area to engine area.

An important object of the present invention is to overcome the foregoing and various other disadvantages of prior practice by providing a fluid operated pump having a high ratio of pump area to engine area, i.e., a pump area to engine area ratio of at least 3:1, and to utilize a correspondingly high operating fluid pressure. As will appear hereinafter, the operating fluid pressure utilized in accordance with the present invention may attain values as high as 20,000 to 25,000 p.s.i. gauge or more, depending on the production rate, the pump depth setting, the specific ratio of pump area to engine area employed, the sizes of the tubings through which the operating fluid flows, and on other factors to be considered.

Numerous advantages and new results are derivable from the high pressure operation, which may logically be referred to as "super pressure" operation, attainable as a consequence of providing a fluid operated pump with a pump area to engine area ratio of 3:1, or higher.

For example, fluid friction losses in the tubings through which the operating fluid circulates are greatly reduced from those experienced with the low pump area to engine area ratios and the resultant low operating fluid pressures employed heretofore. Consequently, the present invention greatly reduces the power requirements of the hydraulic pumping system in which it is embodied and thus greatly increases over-all efficiency, which is an important advantage.

Since the present invention results in substantial reduc-

tions in operating fluid friction losses, smaller tubings for the operating fluid may be employed, which has the advantage of materially reducing the cost of the system. Super pressure operation also markedly increases the capacity of the pump, or the same capacity may be attained with a much smaller unit.

Factors such as the foregoing enable the present invention to reduce drilling and casing costs for a specified pumping capacity as the result of reductions in tubing and pump sizes since a smaller well bore may be used. Expressed differently, the present invention results in a minimum capital investment in drilling and casing the well, and in the hydraulic pumping system, per unit of production capacity.

Another feature of the invention is that the quantity of operating fluid required per unit of production capacity is minimized so that the system for supplying the operating fluid under pressure is reduced in size. This further reduces the over-all capital investment per unit of production capacity.

Another important advantage of the invention is that the surface lines for conducting operating fluid to and from the well may be materially smaller. This still further reduces capital costs per unit of production capacity, particularly where one source of operating fluid serves a number of wells so that the total length of surface lines may be quite large.

Another advantage of super pressure operation is that, as will be explained in more detail hereinafter, the pressure utilized maintains the viscosity of the operating fluid substantially constant throughout the system, i.e., the pressure utilized increases the viscosity to an extent sufficient to substantially offset the reduction in viscosity due to the normal increase in temperature with well depth. Maintaining the viscosity substantially constant throughout the system in this manner limits leakage losses in the pump and improves lubrication, which are important features.

Another and extremely important advantage of the present invention is that utilizing a high pump area to engine area ratio and a high operating fluid pressure minimizes the size of the engine section of the fluid operated pump so that the size of the pump section thereof is limited substantially only by the over-all dimensions of the pump. The result of this is that the pump section may be designed solely on the basis of considerations related to efficient pumping, there being no necessity for a compromise in the design of the pump section resulting from the necessity for allocating a great deal of the space available in the fluid operated pump to the engine section thereof, as in the case of prior fluid operated pumps. Thus, the present invention provides a pump section having large passages for the production fluid, large valves, and the like, all of which minimize fluid friction losses with respect to production fluid flow through the pump.

The super pressure operation of the present invention attains particular utility when applied to a fluid operated pump wherein the engine and pump piston means comprises a single plunger having a large axial passage therethrough for the production fluid and carrying a large working valve which prevents flow through such passage during the working stroke of the plunger, the housing of the pump being provided with a correspondingly large standing valve, in either the inlet or the outlet of the pump, which prevents backflow into the well during the return stroke of the plunger. By employing a ratio of pump area to engine area of 3:1, or higher, with such a pump, the diameter of the axial, production-fluid passage through the combined engine and pump plunger is a substantial proportion of the over-all diameter of the plunger. As will be apparent, this reduces production-fluid friction losses through the pump to a minimum, which is an important advantage.

While the fluid operated pump of the invention may take other forms, the invention is particularly applicable

to the pump disclosed in my aforementioned copending application. In this pump, the engine and pump piston means comprises a single plunger the upper end of which provides the pump area, the engine area being a small, downwardly-facing annulus which encircles the large axial passage for the production fluid. With a ratio of pump area to engine area of at least 3:1 in accordance with the invention, the size of this downwardly-facing annulus which forms the engine area is quite small so that the diameter of the axial production-fluid passage through the plunger is a substantial proportion of the over-all diameter of the plunger to minimize fluid friction losses.

With this pump, the working stroke of the plunger is effected by applying the exhaust pressure to an upwardly-facing annular area of the plunger while applying the operating fluid pressure to the downwardly-facing annular engine area mentioned, these two annular areas being located at the ends of a reduced-diameter section of the plunger. The return stroke of the plunger is effected in the presently preferred embodiment of the invention by applying the operating fluid pressure to the upwardly-facing annular area while still applying the operating fluid pressure to the downwardly-facing annular area, or by applying the exhaust pressure to both of these areas. The upwardly-facing annular area is very slightly larger than the downwardly-facing annular area so that the return stroke of the plunger results from the application of the operating fluid pressure, or the exhaust pressure, to both of these annular areas.

Another advantage of utilizing a fluid operated pump having the structure disclosed in my aforementioned copending application in connection with a ratio of pump area to engine area of 3:1 or higher, is that the engine valve means, which produces reciprocatory movement of the plunger by alternately applying the exhaust pressure and the operating fluid pressure to the upwardly-facing annular area of the plunger, is located alongside of and spaced from the plunger. This further eliminates interference with the pump section of the fluid operated pump by the engine section thereof so that the pump section design is determined virtually entirely by pump considerations alone.

The foregoing objects, advantages, features and results of the present invention, together with various other objects, advantages, features and results thereof which will be evident to those skilled in the fluid operated pump art in the light of this disclosure, may be attained with the exemplary embodiment of the invention described in detail hereinafter and illustrated in the accompanying drawings, in which:

Fig. 1 is a view, partially in vertical section, of an installation of a fluid operated pumping system of the invention in a well;

Fig. 2 is an enlarged, horizontal sectional view taken along the arrowed line 2-2 of Fig. 1;

Figs. 3, 4, 5 and 6 are semidiagrammatic, vertical sectional views of fluid operated pumps having different ratios of pump area to engine area, these ratios for the pumps of these figures being 1.065:1, 2:1, 3:1, and 5:1, respectively;

Fig. 7 is a graph showing the manner in which an increasing ratio of pump area to engine area results in an increase in the diameter of a rod which interconnects piston elements of a combined engine and pump plunger, and thus results in an increase in the diameter of an axial production-fluid passage through such plunger;

Fig. 8 is a graph illustrating the manner in which an increasing ratio of pump area to engine area results in a decrease in the operating fluid pressure loss in the system due to friction for different tubing sizes; and

Fig. 9 is a graph illustrating the effect of an increasing ratio of pump area to engine area on the reciprocal of the fluid pressure loss in percent of the actual or total operating fluid pressure.

Referring first to Figs. 1 and 2 of the drawings, the present invention is illustrated therein as installed in a well provided with a casing 10 having perforations 12 through which production fluid may flow into the casing from the productive formation, not shown, into which the well is drilled. The casing 10 is surmounted by a casing head 14 from which operating fluid supply and return tubings 16 and 18 and a production tubing 20 are suspended. Connected to the lower ends of these tubings is a bottom-hole pump housing 22.

Hydraulically movable through the production tubing 20 between the surface and an operating position within the housing 22 is a free, fluid operated pump unit 24. As will be discussed in more detail hereinafter, the pump unit is of the reciprocatory type and includes a pump section for pumping fluid from the well upwardly through the production tubing 20 to the surface, the production tubing being large as compared to the supply and return tubings to permit the pumping therethrough of a large volume of production fluid with minimum fluid friction losses and to permit the use of a pump unit of maximum diameter. The pump section of the pump unit 24 is actuated by a fluid operated engine section. The latter is actuatable by an operating fluid under pressure delivered thereto through the supply tubing 16, the spent operating fluid being discharged at exhaust pressure into the return tubing 18 which conveys it to the surface. Since, as will be discussed hereinafter, the engine section of the pump unit 24 is actuated with a small volume of operating fluid at a very high pressure, the supply and return tubings 16 and 18 are small relative to the production tubing 20.

The operating fluid pressure in the supply tubing 16 and the exhaust pressure in the return tubing 18 are applied to the engine section of the pump unit 24, under the control of an engine valve means 26, in a manner to produce reciprocatory movement of a combined engine and pump piston means 28, Figs. 3 to 6, within the pump unit 24. The engine valve means 26 is incorporated in a free valve unit 30 which is hydraulically movable through the supply tubing 16 between the surface and an operating position in the housing 22 alongside of and spaced laterally from the pump unit 24, the pump and valve units thus being movable between their side-by-side operating positions and the surface independently of each other.

The supply, return and production tubings 16, 18 and 20 are connected at their upper ends to a control device 32 having therein valve means, not shown, operated by a handle 34 for connecting the supply, return and production tubings to supply, return and production lines 36, 38 and 40 in various ways. The supply line 36 is connected to a suitable source of operating fluid under pressure, such as surface pumping equipment, not shown, while the return and production lines 38 and 40 are connected to suitable points of disposal, not shown, for the spent operating fluid and the production fluid. When the pump and valve units 24 and 30 are in operation in the well, the handle 34 is moved to a position such as to cause the valve means in the control device 32 to connect the supply, return and production tubings 16, 18 and 20 to the supply, return and production lines 36, 38 and 40, respectively. However, under other operating conditions, such as removal and/or installation of the pump unit 24 and/or the valve unit 30, the handle 34 may be moved to other positions to cause the valve means within the control device 32 to interconnect the supply, return and production tubings 16, 18 and 20 and the supply, return and production lines 36, 38 and 40 in other ways, as required by the particular operation to be performed.

Surmounting the control device 32 and closing the upper ends of the supply and production tubings 16 and 20 are closures 42 and 44 which are removable to permit insertion of the valve and pump units 30 and 24 into the supply and production tubings 16 and 20, respectively, or to permit removal of the valve and pump units from

the supply and production tubings. The closures 42 and 44 may be provided with valve-unit and pump-unit catchers, respectively, for catching the valve and pump units as they are moved to the surface hydraulically from 5 their operating positions within the housing 22.

The foregoing merely constitutes a general description of the structure and operation of the hydraulic pumping system of the invention, it being unnecessary to describe this system in more detail herein, except for certain details of the pump unit 24, since it is fully described in my aforementioned copending application. Accordingly, reference is hereby made to such copending application for a more complete disclosure of any subject matter not described in specific detail hereinafter.

15 Turning now to Fig. 3 of the drawings, the pump unit 24 is shown semidiagrammatically as including a housing 46 which provides a cylinder means 48 for the combined engine and pump piston means 28. The cylinder means 48 is provided at its lower end with an inlet 50 which communicates with the interior of the casing 10 at the level at which the pump housing 22 is set, the inlet being provided with a standing valve 52 which prevents backflow into the well. At the upper end of the cylinder means 48 is an outlet 54 which communicates with 20 the lower end of the production tubing 20 so that production fluid pumped from the well through the inlet 50 and the outlet 54 is discharged into the production tubing for conveyance thereby to the surface. While the standing valve 52 is shown as located at the inlet 50, 25 it may be located at the outlet 54 also, as disclosed in my aforementioned copending application.

The combined engine and pump piston means 28 comprises a single plunger 56 having an intermediate section of reduced diameter to provide upper and lower piston 30 or plunger elements 58 and 60 interconnected by a rod 62. The plunger 56 is provided with an axial production-fluid passage 64 through which the production fluid may flow from the inlet 50 to the outlet 54 along a straight, axial path, backflow through the passage 64 being prevented by a working valve 66 carried by the plunger.

The plunger 56 is provided with an upwardly facing pump area 68, equal to the entire area of the upper end of the upper piston element 58, which supports the entire column of production fluid in the production tubing 20 during the upward or working stroke of the plunger, and which moves the production column upwardly through the production tubing during such stroke. As will be apparent, the working valve 66 is closed during the upward, working stroke of the plunger 56 and the standing valve 52 is open to permit flow of production fluid from the well into the lower end of the cylinder means 48 through the inlet 50 during such stroke. During the downward or return stroke of the plunger 56, the standing valve 52 is closed to prevent backflow into the well and the working valve 66 is open to permit displacement of fluid from below the plunger 56 through the axial passage 64 into the cylinder means 48 above the plunger. Thus, the pump area 68 of the plunger 56 and the standing and working valves 52 and 66 constitute the pump section of the pump unit 24.

The engine section of the pump unit 24 includes a downwardly-facing annular area 70 which is formed by the lower end of the upper piston element 58 and which 65 encircles the rod 62. The engine area 70, in the particular construction illustrated, is constantly exposed to operating fluid pressure in a cylinder 72 in which the piston element 58 reciprocates, the cylinder 72 being in constant communication with the supply tubing 16 through a port 74 and the engine valve means 26 in a manner more fully described in the aforementioned copending application. The engine section of the pump unit 24 also includes an upwardly-facing annular area 76 which is formed by the upper end of the lower piston element 60 and which encircles the rod 62. The annular area 76 is

exposed to fluid pressure in a cylinder 78 in which the lower piston element 60 is reciprocable, the cylinder 78 being separated from the cylinder 72 by a partition 80 having an axial bore 82 therethrough for the rod 62. The cylinder 78 is provided with a port 84 which is alternately connected to the supply tubing 16 and the return tubing 18 by the engine valve means 26 in a manner more fully described in the aforementioned copending application. Consequently, the area 76 is alternately subjected to the operating fluid pressure in the supply tubing 16 and the spent operating fluid or exhaust pressure in the return tubing 18.

With the foregoing construction, it will be apparent that when the area 76 is exposed to the exhaust pressure, the operating fluid pressure constantly acting on the engine area 70 produces the working stroke of the plunger 56. The annular area 76 is slightly larger than the engine area 70 so that, when the operating fluid pressure is applied to the annular area 76, the return stroke of the plunger 56 is effected despite the fact that the operating fluid pressure is constantly applied to the engine area 70. The necessary difference between the engine area 70 and the annular area 76 may be provided by making the lower piston element 60 a few thousandths of an inch larger than the piston element 58.

It will be understood that instead of constantly applying the operating fluid pressure to the area 70 and alternately applying the operating fluid pressure and the exhaust pressure to the area 76, the working and return strokes may be effected by alternately applying the operating fluid pressure and the exhaust pressure to the area 70 while constantly applying the exhaust pressure to the area 76.

In the pump unit 24 shown in Fig. 3 of the drawings, the ratio of the pump area 68 to the engine area 70 is only 1.065:1 and, as will be apparent, such a low pump area to engine area ratio necessitates making the axial passage 64 of small diameter, and necessitates a correspondingly small working valve 66, the standing valve 52 also being correspondingly small since there would be no point in making it much larger than the working valve. It will be noted that the axial passage 64 in Fig. 3 is of small diameter even though the wall thickness of the tubular rod 62 has been reduced to an absolute minimum.

In Figs. 4, 5 and 6 of the drawings, the pump unit 24 is shown as having pump area to engine area ratios of 2:1, 3:1 and 5:1, respectively, the same reference numerals being utilized throughout Figs. 3 to 6 in view of the correspondence of parts. Progressively increasing the ratio of the pump area 68 to the engine area 70 from 1.065:1 to 5:1 results in progressively increasing the outside diameter of the tubular connecting rod 62. This provides for a progressive increase in the diameter of the axial production-fluid passage 64 through the plunger 56, and corresponding progressive increases in the sizes of the standing valve 52 and the working valve 66. Also, the wall thickness of the tubular connecting rod 62 is shown as progressively increasing with the progressively increasing ratio of the pump area 68 to the engine area 70 to provide progressively improved structural characteristics.

As will be apparent, increasing the pump area to engine area ratio greatly reduces the fluid friction losses through the axial production-fluid passage 64 because of the increased diameter of this passage and because of the increased sizes of the standing valve 52 and the working valve 66. With the 1.065:1 ratio of Fig. 3, the outside diameter of the plunger rod 62 is only 25% of the outside diameter of the piston element 58 of the plunger 56. Under these conditions, the diameter of the axial passage 64 is necessarily so small that the production-fluid velocity therethrough must attain a value of more than twenty times the velocity of the plunger 56. This results in serious fluid friction losses, and presents a serious

limitation on plunger speed and pump capacity. By going to the 2:1 ratio of Fig. 4, a substantial improvement results, the tubular plunger rod 62 in this case having a diameter equal to 70.7% of the diameter of the plunger 56. Under these conditions, the production-fluid velocity through the axial passage 64 is only approximately four times the plunger velocity, with a wall thickness for the rod 62 adequate to provide the necessary structural strength.

However, optimum results are achieved by utilizing a ratio of the pump area 68 to the engine area 70 of 3:1, or higher, as shown in Figs. 5 and 6. With such ratios, the annular engine area 70 if reduced in size to such a small proportion of the total cross-sectional area of the piston element 58 of the plunger 56 that satisfactorily low production-fluid velocities through the axial passage 64, relative to plunger velocity, are achieved. Also, the working valve 66 has the best proportions with a ratio of 3:1, or higher, and the fluid velocities through the working valve seat and in the annulus between the working valve and the cylinder can be made approximately equal, which is desirable. These factors all contribute to reducing fluid friction losses through the plunger 56 to a minimum with a pump area to engine area of 3:1 or higher.

Referring to Fig. 7 of the drawings, the graph presented therein illustrates the effect of increasing the ratio of the pump area 68 to the engine area 70 on the ratio of the diameter of the tubular plunger rod 62 to the diameter of the piston element 58 of the plunger 56, the latter ratio being expressed in percentages. As Fig. 7 clearly shows, the outside diameter of the tubular plunger rod 62, and thus the diameter of the axial passage 64 and the sizes of the standing and working valves 52 and 66, increase rapidly with an increase in the ratio of the pump area 68 to the engine area 70 until a ratio of 3:1 is attained, the ratio of plunger rod diameter to plunger diameter increasing slowly with an increase in the ratio of the pump area to the engine area above 3:1. In fact, the curve of Fig. 7 becomes so nearly flat by the time a ratio of the pump area 68 to the engine area 70 of 5:1 is achieved that, for all practical purposes, a ratio of 5:1 may be regarded as a maximum.

It will be apparent that the side-by-side locations of the pump unit 24 and the valve unit 30 are important in achieving the best results with a ratio of the pump area 68 to the engine area 70 of 3:1, or more, since the engine valve unit does not interfere with the pump unit. This permits taking maximum advantage of the large production-fluid passage 64 and the large working valve 56 permitted by the present invention since a correspondingly large standing valve 52 and correspondingly large passages throughout the remainder of the pump unit 24 may be utilized.

Utilizing a pump area to engine area ratio of at least 3:1 requires a correspondingly high operating fluid pressure to apply to the plunger 56 the same working-stroke force as is attained with lower ratios and operating fluid pressures. As hereinbefore pointed out briefly, the super pressure operation of the present invention provides new and startling advantages and economies over any presently used hydraulic pumping system which may best be shown by comparing the results of super pressure operation with the result of operation at conventional pressures. The comparison will be limited to one set of operating conditions, it being understood that similar comparisons may be made for other sets of conditions.

Outlining the set of conditions under which the comparison mentioned will be made hereinafter, it will be assumed that the pump unit 24 is a 2½ inch unit, i.e., one which may be inserted into a 2½ inch production tubing 20. The comparison will further be based on a pump depth setting of 10,000 feet and a production rate of 350 barrels per day. Also, it will be assumed that the mean surface temperature is 60° F. and that the

temperature gradient in the well is 1° F. for each 60 ft. of depth, the temperature of course increasing with depth. The production fluid is assumed to have a viscosity of 60 SSU at 100° F. and a specific gravity of 0.87.

Assuming the foregoing set of conditions, the fluid friction losses throughout the system were computed in terms of pressure drops in pounds per square inch. In computing the fluid friction losses, each of the supply, return and production tubings 16, 18 and 20 was divided into sections of 1,000 feet in length and the fluid friction loss was computed for each such section of each tubing for the conditions obtaining at the midpoint thereof. The total fluid friction loss in each of the tubings was then obtained by adding the fluid friction losses in each of the 10 sections into which it was divided.

Fluid friction loss computations were made in the foregoing manner for pump area to engine area ratios of 1:1, 2:1, 3:1, 4:1 and 5:1 for three different sets of tubing sizes, viz., a diameter for the production tubing 20 of $2\frac{1}{2}$ inches and diameters for the supply and return tubings 16 and 18 of 1 inch, a diameter for the production tubing 20 of $2\frac{1}{2}$ inches and diameters for the supply and return tubings of $\frac{3}{4}$ inch, and a diameter for the production tubing of $2\frac{1}{2}$ inches and diameters for the supply and return tubings of $\frac{1}{2}$ inch. For convenience, the sets of tubing sizes will be referred to hereinafter as the $2\frac{1}{2}''$ x 1" system, the $2\frac{1}{2}''$ x $\frac{3}{4}$ " system and the $2\frac{1}{2}''$ x $\frac{1}{2}$ " system, respectively. The comparative results for pump area to engine area ratios of 1:1, 2:1, 3:1, 4:1 and 5:1 for the $2\frac{1}{2}''$ x 1", the $2\frac{1}{2}''$ x $\frac{3}{4}$ " and the $2\frac{1}{2}''$ x $\frac{1}{2}$ " systems are tabulated in Tables I, II, III as follows:

Table I ($2\frac{1}{2}''$ x 1")

Ratio	1:1	2:1	3:1	4:1	5:1
Friction in tubing 20Xratio	7	14	21	28	35
Friction in tubing 16	434	211	201	235	206
Friction in tubing 18	356	112	63	40	30

In the foregoing tables, the item "Ratio" is the ratio of the pump area 68 to the engine area 70. The items "Friction in tubing 20Xratio," "Friction in tubing 16" and "Friction in tubing 18" are the fluid friction losses in the tubings specified in pounds per square inch. It should be pointed out that the friction loss in the tubing 20 is actually the addition to the operating pressure as a

result of this friction. This operating pressure increase includes the pump to engine area ratio factor. For instance, the friction loss in the tubing 20, as shown in Tables I, II and III, is 7 p.s.i. gauge. With a 1:1 ratio this is also a 7 p.s.i. gauge increase in the operating pressure, but with a 2:1 ratio, this becomes 14 p.s.i. gauge, and correspondingly more for the other ratios. The item "Column density differential" is a correction which takes into consideration the fact that the supply column in the tubing 16, being under higher pressure than the return column in the tubing 18, will have a higher density than the return column due to the compressibility of the oil utilized as the operating fluid. The correction represented by the item "Column density differential" is a negative one which reduces the operating fluid pressure required at the lower end of the supply tubing 16. The item "Theoretical operating pressure" represents the operating fluid pressure in pounds per square inch necessary to produce the working stroke of the plunger 56 under the conditions hereinbefore specified in a frictionless system. The "Actual operating pressure" is equal to the "Theoretical operating pressure" plus the "Friction in tubing 20Xratio," the "Friction in tubing 16," the "Friction in tubing 18" and the "Column density differential." The "Net pressure loss" in Tables I, II and III is in each instance the difference between the "Actual operating pressure" and the "Theoretical operating pressure." The item "Loss in percent of actual" is equal to the difference between the "Actual operating pressure" and the "Theoretical operating pressure" multiplied by 100 and divided by the "Actual operating pressure." The item "Reciprocal of loss in percent" is obtained by dividing one by the "Loss in percent of actual."

It should also be pointed out that, in computing the results presented in Tables I, II and III, appropriate corrections were made for changes in friction due to viscosity reductions with temperature increases in the well bore with depth. Also, corrections were made for viscosity changes with pressure based on the average pressures for the ten sections into which each of the tubings 16, 18 and 20 was divided for computation purposes.

The comparative results contained in Tables I, II and III are plotted in Figs. 8 and 9 of the drawings. Fig. 8 is a graph presenting the relation between the "Loss in percent of actual" and the ratio of the pump area 68 to the engine area 70 for the $2\frac{1}{2}''$ x 1", the $2\frac{1}{2}''$ x $\frac{3}{4}$ " and the $2\frac{1}{2}''$ x $\frac{1}{2}$ " systems. Fig. 9 presents in graph form the relationship between the "Reciprocal of loss in percent" and the ratio of the pump area to the engine area for the three systems of Tables I, II and III.

As clearly shown by Tables I, II and III and by Fig. 8, the pressure loss due to fluid friction decreases rapidly as the ratio of the pump area 68 to the engine area 70 is increased. Considering Table I and the corresponding curve of Fig. 8 as an example, it will be seen that while the "Net pressure loss" is 16.4% with a ratio of 1:1, the loss drops to 1.03% at a ratio of 3:1, to 0.626% at a ratio of 4:1 and to 0.625% at a ratio of 5:1. Similar comparisons may be obtained from Tables I, II and III and from Fig. 8.

As Fig. 8 clearly shows, the friction losses for the $2\frac{1}{2}''$ x 1", the $2\frac{1}{2}''$ x $\frac{3}{4}$ " and the $2\frac{1}{2}''$ x $\frac{1}{2}$ " systems reach minimum values at ratios of pump area to engine area of from 4:1 to 5:1 and have substantially reached such minimum values at a ratio of 3:1. However, in each instance, the pressure loss at a ratio of 2:1 is considerably higher, and at a ratio of 1:1 is very much higher. Consequently, it will be apparent that a ratio or pump area to engine area of 3:1 represents a minimum for the purposes of the present invention. On the other hand, a ratio of 5:1 represents a practical maximum because each of the curves of Fig. 8 shows a minimum friction loss at approximately 5:1, the net pressure losses tending to increase slightly above this ratio.

Fig. 9, wherein the "Reciprocal of loss in percent" is

11

plotted versus the ratio of pump area to engine area, also illustrates that a ratio of 3:1 is a minimum value and a ratio of 5:1 is a practical maximum value. It will be noted that, in each instance, the curves of Fig. 9 show a curvature reversal at a ratio of slightly less than 3:1, this reversal being the most pronounced in the curve for the 2½" x 1" system, but existing in the curves for the other two systems also. The three curves virtually flatten out between ratios of 4:1 and 5:1 and peak at a ratio of 5:1 in the same manner as the curves of Fig. 8, thereby establishing the ratio of 5:1 as a practical maximum.

While the hereinbefore-presented comparison between the 16.4% net pressure loss with a 1:1 ratio and the 1.03% net pressure loss with a 3:1 ratio in the 2½" x 1" system strikingly illustrates the advantages resulting from the present invention in drastically reducing fluid friction losses as the result of super pressure operation, an even more striking comparison can be obtained by considering the effect of increasing the production rate from 350 barrels per day with this system to 1,000 barrels per day, all other conditions remaining constant. At a 1:1 ratio, the net friction loss would be increased to approximately 63%, making the power transmission efficiency only 37%, as compared with a power transmission efficiency of 83.6% at a production rate of 350 barrels per day. However, if a 3:1 ratio of pump area to engine area is utilized with a production rate of 1,000 barrels per day in the 2½" x 1" system, then the net pressure loss due to friction is increased from 1.03% to only approximately 7.8% for a high power transmission efficiency of 92%. Thus, it will be seen that the ratio of pump area to engine area of 3:1, or higher, also permits attaining high power transmission efficiencies with high production rates, which is an important feature of the invention.

Another important comparison graphically illustrating the advantages of super pressure operation is the power transmission capacity of a one inch tubing having a length of 10,000 feet. Assuming losses not exceeding 10%, the horsepower capacity of one inch tubing for different ratios of the pump area 68 to the engine area 70 is as follows:

Table IV

Ratio	1:1	2:1	3:1	4:1	5:1
Horsepower	17.5	50	91	140	196

Another important advantage of the present invention is the essential saving in supply tubing and return tubing costs. As will be seen by comparing Tables I and II, the supply and return tubings 16 and 18 may be reduced in size from one inch to ¾ inch with an increase in the net pressure loss from 1.03% to only 5.25%, the increases in net pressure loss being even less at ratios of 4:1 and 5:1. Consequently, with pump area to engine area ratios of 3:1, or higher, the supply and return tubings 16 and 18 may be reduced in size from one inch to ¾ inch with very little sacrifice in power transmission efficiency. Considering the difference in cost of one inch and ¾ inch tubing, utilizing ¾ inch tubing for the tubings 16 and 18 represents a saving of \$1,200 for a 10,000 ft. pump depth. Further cost savings may be realized in this respect by going to ½ inch tubing. With ½ inch tubing, the net pressure loss at a 3:1 ratio is still only 20.3% and is even less with ratios of 4:1 and 5:1. Making this comparison in a little different manner, it will be seen that by using a ratio of pump area to engine area of from 3:1 to 5:1 with ½ inch tubing for the supply and return tubings 16 and 18, the net pressure loss experienced is only slightly higher than that resulting from the use of one inch tubing at a 1:1 ratio (Table I). Thus, very substantial cost savings with respect to the supply and return tubings 16 and 18 are possible with the present invention.

The smaller sizes for the supply and return tubings 16 and 18 which the present invention permits also result

12

in a cost saving from another standpoint. For example, the 2½" x 1" system requires a 7 inch casing, whereas the 2½" x ¾" system requires only a 6 inch casing. In a 10,000 ft. well, this reduction in casing size results in a saving of approximately \$10,000 at present casing costs. Additionally, a smaller well bore is required for 6 inch casing, which represents a further saving in costs.

Considering another advantage of the present invention, by utilizing at least a 3:1 ratio of the pump area 68 to the engine area 70, a much greater pumping capacity is possible than with present fluid operated pumping systems utilizing pump area to engine area ratios in the conventional range. For example, a pump unit which is inserted in a 2½ inch tubing may have a capacity as high as 1,200 barrels per day, as compared with the present maximum of 500 barrels per day. Table V, below, gives the pumping capacities of pump units utilizing a 3:1 ratio at the piston speeds and fluid velocities which have been found to be practical.

Table V

Pump size.....inches.....	1½	2	2½	3	4
Plunger size.....do.....	7/8	13/16	13/4	21/8	23/4
Capacity (b/d.).....	300	600	1,200	1,900	3,200

Another important advantage inherent in the super pressure operation of the present invention is the cushioning effect of the operating fluid. The bulk modulus of compressibility of the crude oil utilized for the operating fluid is approximately 200,000 p.s.i. gauge. At 11,000 p.s.i. gauge, which is approximately the operating fluid pressure at 10,000 ft. with a 3:1 ratio in the 2½" x 1" system, the operating fluid is compressed approximately 5½%. An air system operating at 285 p.s.i. gauge with a range of operating pressure of 15 p.s.i. gauge would be the equivalent, which is a very moderate pressure for an air cushioning system. Thus, a hydraulic system which at low pressure is considered almost incompressible becomes a highly compressible or soft system at the extreme pressures contemplated by the present invention, which is an important feature.

As another illustration of the magnitude of this compressibility, the system discussed in the preceding paragraph requires the addition of 24.7 gallons of operating fluid thereto to bring the pressure from zero up to 11,000 p.s.i. gauge. Remembering that the general example hereinbefore discussed is based on a production rate of 350 barrels per day, the system therefore requires 117 barrels of operating fluid per day with a 3:1 ratio of pump area to engine area. Consequently, 7.25 minutes of operation would be required to compress the operating fluid column in the supply tubing 16 to the full operating pressure of 11,000 p.s.i. gauge. Also, if the pump unit 24 were operating at a normal rate of 71 strokes per minute and were then stopped for one complete stroke with the delivery of operating fluid to the supply tubing 16 continuing, the pressure in the system would increase only 21.3 p.s.i. gauge. Thus, the softness of a fluid operated pumping system embodying the invention is strikingly demonstrated.

Another point of considerable importance is the fact that the extreme pressure operation of the present invention results in only a very slight increase in leakage losses in the pump unit 24. The reason for such a slight increase in leakage losses stems from the fact that super pressure operation greatly increases the viscosity of the operating fluid. For example, if the viscosity of the operating fluid at 10,000 feet at an operating fluid pressure of 4,416 p.s.i., which is the operating fluid pressure set forth in Table I for a 1:1 ratio of pump area to engine area, is 2.9 centistokes, then the viscosity at the same depth and an operating fluid pressure of 11,182 p.s.i. gauge, corresponding to the 3:1 ratio of Table I, is 5.2 centistokes. Thus, while the pressure of 11,182 p.s.i. gauge corresponding to a 3:1 ratio tends to produce

more leakage than the pressure of 4,416 p.s.i. gauge corresponding to a 1:1 ratio, this tendency is partially offset by the corresponding viscosity increase from 2.9 centistokes to 5.2 centistokes resulting from the higher pressure with a 3:1 ratio. It can be shown that the combined effect of the increased leakage due to the increased pressure and the decreased leakage due to the increased viscosity resulting from the increased pressure results in a leakage of only 1.7 units for a 3:1 ratio of pump area to engine area for each unit of leakage with a 1:1 ratio of pump area to engine area. In other words, going from a 1:1 ratio of pump area to engine area to a 3:1 ratio results only in a 1.7:1 increase in leakage losses. Consequently, all of the hereinbefore-discussed advantages of super pressure operation and pump area to engine area ratios of at least 3:1 are attained with only a 1.7:1 increase in leakage in the pump unit 24.

Although various specific illustrative examples have been presented herein, it will be understood that the invention is not to be regarded as limited thereto and is to be accorded the full scope of the following claims.

I claim:

1. In a fluid operated pump, the combination of: cylinder means having upper and lower ends and having an inlet adjacent its lower end and an outlet adjacent its upper end; combined engine and pump piston means reciprocable in said cylinder means and having an axial passage therethrough for production fluid pumped by said pump which communicates at its lower end with said inlet and at its upper end with said outlet, said piston means having at the upper end thereof an upwardly-facing, transverse pump area and having below the upper end thereof a downwardly-facing, annular, transverse engine area which encircles and is spaced radially outwardly from said axial passage, the ratio of said pump area to said engine area being at least 3:1, a working valve carried by said piston means and controlling flow through said passage; a standing valve carried by said cylinder means and controlling flow through one of said inlet and said outlet; and means for applying operating fluid pressure to said engine area.

2. In a fluid operated pump, the combination of: cylinder means having upper and lower ends and having an inlet adjacent its lower end and an outlet adjacent its upper end; combined engine and pump piston means comprising a plunger reciprocable in said cylinder means and having an axial passage therethrough for production fluid pumped by said pump which communicates with said inlet at its lower end and with said outlet at its upper end, said plunger having at its upper end an upwardly-facing, transverse pump area and having intermediate its ends a section of reduced diameter providing a downwardly-facing annular, transverse engine area which encircles and is spaced radially outwardly from said axial passage and providing an upwardly-facing, annular, transverse engine area which also encircles and is spaced radially outwardly from said axial passage, the ratio of said pump area to said downwardly-facing engine area being at least 3:1, said upwardly-facing engine area being slightly larger than said downwardly-facing engine area; a working valve carried by said plunger and permitting upward flow through said axial passage; a standing valve carried by said cylinder means and permitting upward flow through one of said inlet and said outlet; means for constantly applying an operating fluid pressure to said downwardly-facing engine area; and means for alternately applying said operating fluid pressure and an exhaust pressure to said upwardly-facing engine area.

3. In a fluid operated pump, the combination of: cylinder means having upper and lower ends and having an inlet adjacent its lower end and an outlet adjacent its upper end; combined engine and pump piston means comprising a plunger reciprocable in said cylinder means and having an axial passage therethrough for production fluid pumped by said pump which communicates with said

inlet at its lower end and with said outlet at its upper end, said plunger having at its upper end an upwardly-facing, transverse pump area and having intermediate its ends a section of reduced diameter providing a downwardly-facing annular, transverse engine area which encircles and is spaced radially outwardly from said axial passage and providing an upwardly-facing, annular, transverse engine area which also encircles and is spaced radially outwardly from said axial passage, the ratio of said pump area to said downwardly-facing engine area being at least 3:1, said upwardly-facing engine area being slightly larger than said downwardly-facing engine area; a working valve carried by said plunger and permitting upward flow through said axial passage; a standing valve carried by said cylinder means and permitting upward flow through one of said inlet and said outlet; means for constantly applying an operating fluid pressure to said downwardly-facing engine area; and engine valve means located alongside of and spaced laterally from said plunger for alternately applying said operating fluid pressure and an exhaust pressure to said upwardly-facing engine area.

4. In a fluid operated pumping system, the combination of: production and supply tubings set in a well and extending downwardly therein from the surface to a pumping zone; fluid operated pumping means connected to said production and supply tubings in said pumping zone, and provided with an inlet in communication with the well and an outlet in communication with said production tubing, for pumping production fluid from the well through said inlet and said outlet into said production tubing, said pumping means including engine and pump piston means reciprocable through working and return strokes and having a transverse pump area which communicates with said outlet and which supports a column of production fluid extending from said pumping zone to the surface in said production tubing during said working stroke of said piston means, and said piston means having a transverse engine area which faces in the opposite direction from said pump area and which is capable of being acted on by operating fluid under pressure in said supply tubing to produce said working stroke of said piston means, the ratio of said pump area to said engine area being at least 3:1; and means for applying operating fluid pressure from said supply tubing to said engine area.

5. A fluid operated pumping system as set forth in claim 4 wherein said pumping means includes an axial passage for production fluid being pumped which extends through said piston means and which communicates with said inlet and said outlet, said piston means carrying a working valve which controls flow through said axial passage and said pumping means including a standing valve controlling flow through one of said inlet and said outlet.

6. In a fluid operated pump, the combination of: cylinder means having upper and lower ends and having an inlet adjacent its lower end and an outlet adjacent its upper end; combined engine and pump piston means comprising a plunger reciprocable in said cylinder means and having an axial passage therethrough for production fluid pumped by said pump which communicates with said inlet at its lower end and with said outlet at its upper end, said plunger having at its upper end an upwardly-facing, transverse pump area and having intermediate its ends a section of reduced diameter providing a downwardly-facing annular, transverse engine area which encircles and is spaced radially outwardly from said axial passage and providing an upwardly-facing, annular, transverse engine area which also encircles and is spaced radially outwardly from said axial passage, the ratio of said pump area to said downwardly-facing engine area being at least 3:1, said upwardly-facing engine area being slightly larger than said downwardly-facing engine area; a working valve carried by said plunger and per-

mitting upward flow through said axial passage; a standing valve carried by said cylinder means and permitting upward flow through one of said inlet and said outlet; means for constantly applying an exhaust pressure to said upwardly-facing engine area; and means for alternately applying said exhaust pressure and an operating fluid pressure to said downwardly-facing engine area.

7. In a fluid operated pump, the combination of: cylinder means having upper and lower ends and having an inlet adjacent its lower end and an outlet adjacent its upper end; combined engine and pump piston means comprising a plunger reciprocable in said cylinder means and having an axial passage therethrough for production fluid pumped by said pump which communicates with said inlet at its lower end and with said outlet at its upper end, said plunger having at its upper end an upwardly-facing, transverse pump area and having intermediate its ends a section of reduced diameter providing a downwardly-facing annular, transverse engine area which encircles and is spaced radially outwardly from said axial passage and providing an upwardly-facing, annular, transverse engine area which also encircles and is spaced radially outwardly from said axial passage, the ratio of said pump area to said downwardly-facing engine area being

5

10

15

20

at least 3:1, said upwardly-facing engine area being slightly larger than said downwardly-facing engine area; a working valve carried by said plunger and permitting upward flow through said axial passage; a standing valve carried by said cylinder means and permitting upward flow through one of said inlet and said outlet; means for constantly applying an exhaust pressure to said upwardly-facing engine area; and engine valve means located alongside of and spaced laterally from said plunger for alternately applying said exhaust pressure and an operating fluid pressure to said downwardly-facing engine area.

UNITED STATES PATENT OFFICE
CERTIFICATE OF CORRECTION

Patent No. 2,929,327

March 22, 1960

Clarence J. Coberly

It is hereby certified that error appears in the printed specification of the above numbered patent requiring correction and that the said Letters Patent should read as corrected below.

Column 2, line 39, for "comprise" read -- compromise --; column 9, Table II, first column thereof, next to the last line, for "Loss of percent of actual" read -- Loss in percent of actual --; column 12, Table V, first column thereof, last line, for "(b./d.)" read -- (b/d) --; column 13, line 36, for "3:1," read -- 3:1; --.

Signed and sealed this 30th day of August 1960.
